UNITED STATES PATENT OFFICE.

JOHN T. LANCASTER, OF HAVERHILL, MASSACHUSETTS, ASSIGNOR TO UNITED SHOE MACHINERY CORPORATION, OF PATERSON, NEW JERSEY, A CORPORATION OF NEW JERSEY.

UPPER-PULLING MACHINE.

1,362,631.

Specification of Letters Patent. Patented Dec. 21, 1920.

Application filed February 16, 1918. Serial No. 217,572.

To all whom it may concern:

Be it known that I, JOHN T. LANCASTER, a citizen of the United States, residing at Haverhill, in the county of Essex and State 5 of Massachusetts, have invented certain Improvements in Upper-Pulling Machines, of which the following description, in connection with the accompanying drawings, is a specification, like reference characters on the drawings indicating like parts in the several figures.

This invention relates to machines for use in the manufacture of shoes for shaping the shoe upper to the contour of the last. Well-known types of such machines, as commonly 15 constructed, comprise means for pulling the upper over the last, for drawing or laying the margin of the upper over the edge of the sole or insole, and for fastening the 20 margin of the upper in position. An object of this invention is to provide an upper pulling machine having means for securing improved results in the pulling or stretching 25 of the upper with less attention and effort on the part of the operator than in prior constructions.

Although machines have been devised heretofore adapted for use in shaping the upper to the last by successive pulling impulses including a final supplemental pull 30 for insuring conformity of the upper to the contour of the last before it is fastened in position, as shown for example in United States Letters Patent No. 1,169,414, granted 35 on January 25, 1916 upon the application of R. F. McFeely for improvements in pulling-over machines, the operator in the use of such machines has been required to effect or to initiate the supplemental pulling movement 40 of the gripper or grippers manually as an operation independent of the other operative movements of the machine. One important object of this invention is to reduce the expenditure of time and effort on the 45 part of the operator, while retaining the well-known advantages of successive impulses for stretching the upper stock and shaping it closely to the last. To this end the invention provides, as an important feature, novel means constructed and arranged 50 for automatic operation in time relation to other operative movements of the machine for imparting a supplemental pull to the upper. As applied to a well known type 55 of pulling-over machine, the invention, in

its illustrative embodiment, provides means automatically operative, subsequently to the usual yieldingly effected pull on the upper at the sides and the toe of the last and after opportunity has been afforded for adjusting 60 the upper with reference to the last, for imparting in the overdrawing movement of the grippers at the sides of the last an additional final pull of definite extent to stretch the upper effectively and compensate 65 for any possible relaxation in the tension of the upper in the interval between the release of the upper by the grippers and the driving of the tacks to hold the upper in place. 70

A further feature of the invention is to be recognized in novel means for subjecting the upper gripping means of an upper pulling machine to positive control to prevent the tension on the upper from being 75 relaxed during the movement of such means for drawing the margin of the upper over the sole. In the construction shown, including the usual yielding connections between the side grippers and their operating 80 cams for effecting the first updraw movement, novel means is provided for preventing movement of these grippers in the direction of the plane of the shoe bottom in their overdrawing movement, such means in the 85 illustrative construction serving also to impart to the side grippers a supplemental updraw movement such as above described in their movement to draw the upper over the margin of the sole. 90

In the provision in an upper pulling machine of means for subjecting the upper to a pull the final portion of which is positive or unyielding important advantages are involved as insuring the proper degree of tension in the upper at the time of the upper fastening operation and as contributing to uniformly satisfactory results in the pulling of different uppers, aside from such additional advantages as are involved in a 100 machine of the type herein shown in pulling by successive impulses; and in a further aspect an important feature of the invention is to be recognized in a novel organization of means for pulling an upper yieldingly and then unyieldingly, the machine shown having controlling means automatically operative at a determinate time in the cycle to supplement the yielding pull with an unyielding pull. 105 110

Still another feature of the invention resides in a novel combination of means whereby the upper may be pulled manually and then by power in successive operations of 5 the gripper or grippers.

The above and other features of the invention, including certain more important details of construction and combinations of parts, will now be described with reference 10 to the accompanying drawings and pointed out in the claims.

In the drawings,

Figure 1 is a view in side elevation of a machine in which the invention is embodied, 15 Fig. 2 is a view of a portion of the machine in front elevation, with parts shown in vertical section, this view illustrating an intermediate stage in the cycle of operations of the machine,

Fig. 3 is a plan view, partly in section, of mechanism with which the machine is provided for effecting a supplemental updraw movement of the grippers, and

Fig. 4 is a perspective view of a portion 25 of the mechanism shown in Fig. 3.

The machine herein shown, which is of a type more fully illustrated and described in Patent No. 1,029,387 granted on June 11, 1912 upon an application of R. F. McFeely, 30 comprises a driving shaft 2 the rotation of which is controlled by a clutch rod 4, the shaft having the usual cams by means of which movement is imparted to the various instrumentalities for operating upon the 35 shoe materials, including the toe gripper 6 and side grippers 8 for engaging and pulling the upper on a last positioned by means of the sole rest 10 and the heel rest 12. Each of the side grippers 8, of which only 40 one is seen in the drawings, is connected to an updraw lever 14 which is operated to cause the gripper to pull or "updraw" the upper through downward movement of a rod 16 effected by a cam on the shaft 2, the 45 connections between the lever and the rod comprising a spring 18 which bears at one end on the lever and at its other end on a nut 20 on the rod, from which it results that the pull on the upper effected by the movement 50 of the rod 16 is a yielding one the strength of which depends upon the tension of the spring 18. Only one side gripper operating rod 16 and spring 18 are shown in the drawings, but it will be understood that 55 the lever 14 on the opposite side of the machine from that in view in Fig. 1 is operated by other yielding connections such as above described and that the operations of both side grippers are substantially simultaneous. The toe gripper 6 is operated by 60 a lever 22 and yielding connections similar to those for operating the side grippers.

In order that the updraw movement of the levers 14 effected through the tensioned 65 springs 18 may be suitably retarded and

controlled to prevent tearing the upper and to afford the opportunity for adjusting the upper on the last while the upper is under a suitable tension, the machine is provided with means for controlling the movement of 70 the levers 14. To this end each lever 14 is embraced by a yoke 24 having a semi-spherical bearing member 26 fitting in a bearing formed in a bar 28, the bar having a shank 30 midway between its opposite ends which 75 is swiveled in a block 32 fast on a rock shaft 34, this construction permitting the bar 28 to adjust itself to different relative positions of the levers 14. On one end of the rock shaft 34 is a segmental gear 36 the 80 teeth of which are in mesh with the teeth of a similar gear 38 to which is secured a hand lever 40, the hand lever and the gear 38 being pivoted on a fulcrum rod 42. Connected to the hand lever 40 is a piston 44 which 85 coöperates with a cylinder 46 to provide a dash pot to retard the updraw movement of the levers 14 effected through the action of the springs 18. This construction serves to obviate a too sudden pull upon the upper 90 such as might tend, in some cases, to tear the stock, and also affords the operator an opportunity to observe the progress of the stretching action of the grippers and in case of apparent danger of tearing the stock 95 to oppose resistance to the movement of the gripper levers, under the action of the springs 18, by pressure upon the hand lever 40, thus rendering the springs ineffective to move the levers as far as they otherwise 100 would during the upper pulling operation. It will be understood that after the machine has come to rest at the end of the updraw movement the handle 40 may, in any case, be 105 safely released by the operator, since the friction of the parts, the action of the dash-pot and the resistance of the upper stock are sufficient to prevent such subsequent movement of the updraw levers under the force of the springs 18 as to cause the upper to be 110 stretched to the danger point. While the machine is at rest with the upper under tension, the hand lever 40 may be further 115 moved toward the rear if the condition of the upper stock renders it advisable, to increase the tension on the sides of the upper, the construction thus affording means whereby a further positive pull upon the upper at the sides of the last may be effected manually. Although the springs 18 necessarily expand to take up such manual movement of the updraw levers 14 and are effective, in a considerable degree, to retain the levers in such position as they may assume in consequence of the operation of the 120 hand lever 40, the machine is provided further with a catch 48 arranged to be operated by a lever 50 fulcrumed on the hand lever 40 to cause the catch to engage ratchet teeth 52 and through the connections described be- 130

tween the hand lever 40 and the updraw levers 14 lock the updraw levers against retraction. The catch 48 is normally disengaged from the ratchet 52 through the action 5 of a light spring 53 and may be moved into engagement with the ratchet at the will of the operator. The frictional engagement of the catch and the teeth serves to keep the catch in locking position until a further up- 10 draw movement is imparted to the grippers as hereinafter explained.

The machine as thus far described, in its essential details of construction and manner of operation, is similar to that shown 15 and described in the McFeely Patent No. 1,169,414 hereinbefore referred to, except as the details of the construction are modified for the purposes of this invention, and it is in a machine having these characteris- 20 tics that the present invention may well be embodied with desirable results, although it should be understood that the invention in its broader aspects is not restricted in scope by the limitations of the prior construc- 25 tion. In carrying out the objects of the invention means is provided in the illustrative machine for imparting to the side gripper levers 14 an automatic updraw movement independently of the action of the 30 springs 18 and subsequently to the movement effected by the springs. The machine is constructed to cause this supplemental updraw movement of the levers 14 to take place during the usual inward swinging 35 movement of the side grippers relatively to their operating levers whereby the margin of the upper is drawn over the bottom of the last prior to the operation of the tacking devices, such overdrawing movement of 40 the side grippers and of the toe gripper being effected by the action of overdraw springs 47 which press inwardly against the different gripper bars, supplemented by inward pressure of the overlaying devices carried by the tacker arms 49. It will be under- 45 stood that this overdrawing movement of the side grippers results from the retraction of the usual gripper controlling slide 51 (Fig. 1) under control of a member 55 50 which is connected to the toe and side tacker arms 49 and is moved rearwardly to swing these arms toward the shoe. Such movement of the member 55 is effected through a rack 54 formed on its rear end portion and 55 engaged by a pinion 56 on a rock shaft 58 which receives its movement by a rack and pinion connection from a lever 60 operated by a cam on the shaft 2, as more fully disclosed in Patent No. 1,029,387. On one end 60 of the shaft 58 is secured a segmental gear 62, the teeth of which are in mesh with the teeth of a similar gear 64 from which movement is imparted at the proper time to the rock shaft 34 through connections comprising a link 66 connected at one end to an arm

68 on the rock shaft and at its other end to an arm 70 keyed to a barrel 72 which is mounted both to turn and to slide lengthwise in a bearing in the frame, the barrel 72 having secured thereto a clutch member 74 provided with teeth which are arranged to engage similar teeth on a co-operating clutch member 76 secured to the gear 64. The gear 64 is mounted to turn on a sleeve member 78 which is slidable lengthwise in 75 a bearing in the frame, and within the sleeve 78 is a clutch controlling rod 80 enlarged at one end for engagement with an internal flange 82 in the sleeve. On the outside of the sleeve 78 is a flange 84 which is received within a recess in the gear 64 on the end adjacent to the clutch member 76 and thus causes the gear and the clutch member to move axially with the sleeve while permitting them to turn on the sleeve. The 80 rod 80 is extended through the clutch member 74 and the barrel 72, the outer end portion of the rod having a bearing in a nipple 86 threaded adjustably in the barrel. A spring 88 bearing at one end on the flange 82 and at its other end on the nipple 86 serves to position the barrel 72 and the sleeve 78 and rod 80 normally in such relation as to separate the clutch members 74 and 76, a stop 90 on the end of the rod 80 90 determining by engagement with the end of the nipple 86 the distance by which the clutch members are separated. Both clutch members 74 and 76 together with the barrel 72, the sleeve and the gear 64 may thus be 100 moved a limited distance axially by the endwise movement of the rod 80 without causing relative movement of the clutch members, the spring 88 being of sufficient strength to keep the clutch members 105 separated during such axial movement. Upon engagement, however, of the barrel 72 with a stop 92 threaded adjustably in the frame, movement of the barrel and the clutch member 74 toward the left (Fig. 3) will be 110 stopped and further movement of the rod 80 in the same direction will then cause the clutch member 76 to engage the member 74, whereupon the gear 64 will impart movement through the connections described to 115 the rock shaft 34 to cause a positive updraw movement of the levers 14. Such clutch actuating movement of the rod 80 is effected by means of a cam 94 on the shaft 2 in engagement with a roll 96 carried by 120 the rod, the rod carrying also a stem 98 slidable in a bearing in the frame and surrounded by a spring 100 which tends to move the rod and the associated parts in the direction of the cam. It will be under- 125 stood that the gear 64 is sufficiently wide to cause it to remain continuously in engagement with the gear 62. The arm 70 is restrained from axial movement with the barrel 72 by engagement with the bearing on 130

one side and with a stop member 102 on the other side, and the key connection 104 between the barrel and the arm permits the barrel to slide relatively to the arm. Adjustment of the stop 92, it will be apparent, serves to vary the distance which the rod 80 must move before the clutch members 74, 76 are engaged and therefore to determine the extent of the supplemental updraw movement of the side grippers and the point in the cycle when the locking of the grippers against retractive movement takes place, the length of the teeth on the clutch members being sufficient to permit such variation in the timing of the clutch. In order to retain the stop 92 in adjusted position the machine is provided with a dog 105 arranged for engagement with one of a series of notches in the periphery of the stop. The stop 90 on the end of the rod 80 serves, as explained, to determine the relative positions of the clutch members 74, 76 when these members are disengaged, as well as to determine the tension of the spring 88. In order further to insure that whatever tension may be put upon the upper in the supplemental updraw movement shall be retained until the grippers have released the upper, the barrel 72 has a series of teeth 106 cut within its peripheral outline and a pawl 108 on the frame coöperates with these teeth to retain the barrel and consequently the updraw levers 14 temporarily in the position to which they are moved by the action of the gears 62 and 64. When the parts are in their idle positions a portion of the pawl rests upon the cylindrical periphery of the barrel 72 and the pawl is thus positioned out of engagement with the teeth. When the barrel receives its endwise movement through the action of the cam 94 on the rod 80, the teeth 106 are moved into position to permit the pawl to engage them and the pawl then becomes effective to retain the barrel in the position to which it is turned. In the use of the machine the operator positions the last and the upper and causes the first updraw movement to take place in the usual manner by the actuation of the machine clutch. Such movement may be retarded and controlled, if necessary, by the manipulation of the hand lever 40 as hereinbefore explained. While the machine is at rest with the upper under the tension of the springs 18, adjustment of the upper may be effected as usual by manipulation of the updraw levers and the tension on the stock at the sides of the last may be relaxed somewhat or may be further increased, as conditions demand, by the operation of the hand lever 40. If the hand lever is moved to increase the tension on the stock, it may be locked against retraction by setting the catch 48 in engagement with the ratchet 52. Upon the actuation of the clutch to effect

the final stage of the cycle of operations of the machine, movement is imparted to the gear 64 through the operation of the lever 60, as explained, and at a time in the movement of the gear determined by the adjustment of the stop 92, which may be after the grippers have begun their overdraw movement, the clutch 74, 76 is rendered effective to transmit movement from the gear to the side updraw levers 14. It will be evident that upon the engagement of the clutch members 74, 76 the side grippers are entirely under the control of the lever 60 through the unyielding connections between this lever and the grippers and that the springs 18 have no influence upon the positions of these grippers in the final updraw movement. In consequence of this construction and arrangement positive control of the side grippers is insured to prevent them from relaxing in any substantial degree the tension on the upper during their movement to draw the upper over the margin of the sole. Furthermore, a positive additional updraw movement of the grippers of a predetermined extent is effected in the manner described to stretch the upper finally to the last immediately prior to the operation of the tacking devices, and this final updraw is effected entirely automatically without any attention on the part of the operator. This movement of the grippers is accompanied necessarily, in the illustrative construction, by a further rearward movement of the hand lever 40, the catch 48 being retracted by the spring 53 as soon as it is released from pressure upon the ratchet teeth 52.

It will be understood that the final updraw movement and the overdraw movement of the grippers, as well as the movement of the tacking devices to tacking position, take place through a movement of the lever 60 in one direction, the grippers releasing their hold upon the stock immediately prior to the driving of the tacks. The reverse movement of the lever 60 then takes place and the various parts of the machine are returned to starting position, the cam 94 in the meantime releasing the rod 80 and permitting the clutch members 74, 76 to separate in response to the action of the spring 88, thereby releasing the side grippers again to the control of the updraw springs 18.

While the invention is herein illustrated as applied to the side grippers of a pulling-over machine, it will be evident that important advantages are involved which are not dependent upon the characteristic features of a machine of the particular type shown nor upon pulling the upper at the sides, and it will be understood that in many of its aspects the invention is not limited to the illustrative embodiment.

Having described the invention, what I

claim as new and desire to secure by Letters Patent of the United States is:

1. A machine of the class described having, in combination, a gripper for engaging an upper, means for operating said gripper to pull the upper over a last and then to draw the margin of the upper inward over the bottom of the last, and means automatically operative in time relation to the over-drawing movement of the gripper for operating the gripper to impart to the upper a supplemental pull in said overdrawing movement. 75
2. A machine of the class described having, in combination, a gripper for engaging an upper, yielding means for operating the gripper to pull the upper over a last, means for moving the gripper to draw the margin of the upper inward over the bottom of the last, and means for subjecting the gripper to positive control irrespective of the influence of said yielding means and for moving it further to pull the upper in said over-drawing movement. 80
3. A machine of the class described having, in combination, a gripper for engaging an upper, means for operating the gripper to pull the upper over a last comprising an operating member and connections constructed and arranged to permit relative yielding movement between the gripper and said member, means for moving the gripper to draw the margin of the upper inward over the bottom of the last, and means arranged to be rendered operative after the gripper has begun its overdrawing movement for preventing such relative yielding movement in the gripper operating connections in said overdrawing of the upper. 90
4. A machine of the class described having, in combination, a gripper for engaging an upper, means for operating the gripper to pull the upper over a last comprising an updraw lever and a spring for operating said lever, means for moving the gripper relatively to the lever to draw the margin of the upper inward over the bottom of the last, and positive means arranged to be rendered operative after the gripper has begun its overdrawing movement for determining the position of the lever in said overdrawing movement. 105
5. A machine of the class described having, in combination, a gripper for engaging an upper, means for operating the gripper to pull the upper over a last comprising an updraw lever and a spring for operating said lever, means for moving the gripper to draw the margin of the upper inward over the bottom of the last, and means automatically operative to move said lever independently of the spring to impart to the upper a supplemental pull in said overdrawing movement. 120
6. A machine of the class described hav- 130
- ing, in combination, a gripper for engaging an upper, means for operating the gripper to cause it to pull the upper and to come to rest with the upper under tension, means for imparting to the gripper subsequently a supplemental updraw movement, and power operated means for initiating the operation of said supplemental updraw means. 75
7. A machine of the class described having, in combination, a gripper for engaging an upper, means for operating the gripper to cause it to pull the upper and to come to rest with the upper under tension, means for imparting to the gripper subsequently a supplemental updraw movement, and power operated means for initiating the operation of said supplemental updraw means. 80
8. A machine of the class described having, in combination, a gripper for engaging an upper, power operating means and connections thereto for imparting to the gripper two successive updraw movements, and power operated controlling means for causing the second updraw movement to take place at a definite point in the cycle of operations of the machine. 90
9. A machine of the class described having, in combination, a gripper for engaging an upper, means for imparting to the gripper an initial yielding pull, means for subsequently imparting a positive pull to the gripper, and power operated controlling means for initiating the operation of said positive pulling means at a definite point in the cycle of operations of the machine. 95
10. A machine of the class described having, in combination, a gripper for engaging an upper, means for operating the gripper to pull the upper, power driven mechanism for causing the gripper to draw the margin of the upper over the bottom of the last, and means incidentally operative in the operation of said power driven mechanism for effecting a supplemental pulling movement of the gripper. 110
11. A machine of the class described having, in combination, a gripper for engaging an upper, means for operating the gripper to pull the upper over a last, the gripper being movable to draw the margin of the upper over the bottom of the last, means for controlling the overdrawing movement of the gripper, and mechanism operated by said last named means for imparting a supplemental pulling movement to the gripper. 115
12. A machine of the class described having, in combination, a gripper for engaging an upper, yielding means for operating the gripper to pull the upper over a last, the gripper being movable to draw the margin of the upper over the bottom of the last, means for controlling the overdrawing movement of the gripper, and mechanism 125

- 8
- operated by said last named means for imparting a supplemental positive pull to the gripper.
13. A machine of the class described having, in combination, a gripper for engaging an upper, means for operating said gripper to pull the upper over a last, means for operating the gripper to draw the margin of the upper inward over the bottom of the last, and locking means arranged to be rendered operative by a moving part of the machine after the gripper has begun its overdrawing movement to prevent movement of the gripper toward the plane of the shoe bottom in said overdrawing movement.
14. A machine of the class described having, in combination, a gripper for engaging an upper, means for operating the gripper to pull the upper, means for imparting to the gripper a supplemental updraw movement, said last named means comprising power operated connections including a clutch, and means automatically operative to actuate said clutch at a definite point in the cycle of operations of the machine.
15. A machine of the class described having, in combination, a gripper for engaging an upper, means for imparting an initial pulling movement to the gripper, power operated means including a clutch for imparting a final pulling movement to the gripper, and power operated means for actuating said clutch to cause the final pulling movement to take place.
16. A machine of the class described having, in combination, a gripper for engaging an upper, yielding means for imparting an initial pulling movement to the gripper, positive means including a clutch for imparting a final pulling movement to the gripper, and power operated means for actuating said clutch to cause the final pulling movement to take place.
17. A machine of the class described having, in combination, a gripper for engaging an upper, means for operating the gripper to pull the upper, means for imparting to the gripper a supplemental updraw movement, said last named means comprising power operated connections including co-operating clutch members, means tending to maintain said members in disconnected relation, and power operated means for connecting said members to cause the supplemental updraw movement to take place.
18. A machine of the class described having, in combination, a gripper for engaging an upper, means for operating the gripper to pull the upper, and means for imparting to the gripper a supplemental updraw movement, said last named means being adjustable as to its time of operation to vary the extent of said supplemental movement of the gripper.
19. A machine of the class described hav-

ing, in combination, a gripper for engaging an upper, means for operating the gripper to pull the upper, means for imparting to the gripper a supplemental updraw movement, said last named means comprising power operated connections including a clutch, and means for actuating said clutch adjustable to vary the extent of said supplemental updraw movement of the gripper.

20. A machine of the class described having, in combination, a gripper for engaging an upper, means for operating the gripper to pull the upper over a last, the gripper being movable to draw the margin of the upper over the bottom of the last, means for controlling the overdrawing movement of the gripper, connections between said last named means and the gripper for imparting a supplemental updraw movement to the gripper, said connections including a clutch, and means for actuating said clutch to cause the supplemental updraw movement of the gripper to take place.

21. A machine of the class described having, in combination, grippers for engaging an upper at opposite sides of a last, means for operating said grippers to pull the upper, and automatically controlled power operated means for imparting to said grippers in unison a supplemental positive pull movement to stretch the upper.

22. A machine of the class described having, in combination, grippers for engaging an upper at opposite sides of a last, means for operating said grippers to pull the upper, means for operating the grippers to draw the margin of the upper over the bottom of the last, and means for imparting to the grippers in said overdrawing movement a supplemental upper stretching movement.

23. A machine of the class described having, in combination, grippers for engaging the forepart of an upper at opposite sides of a last, means for operating said grippers to cause them to pull the upper and to come to rest with the upper under tension, starting mechanism for rendering said gripper operating means effective to pull the upper, means operative upon a subsequent actuation of said starting mechanism to lay the margin of the upper over the bottom of the last and fasten it in position, and means arranged to be rendered operative by said last named actuation of the starting mechanism for operating the grippers to impart a supplemental pull to the upper.

24. A machine of the class described having, in combination, grippers for engaging the forepart of an upper at opposite sides of a last, means for operating said grippers to cause them to pull the upper and to come to rest with the upper under tension to enable the operator to adjust the upper on the last, manually operative means for causing the machine subsequently to complete

its cycle of operations on the shoe, and means incidentally operative in said final stage of the cycle of operations for causing the grippers to impart a supplemental pull 5 to the upper.

25. A machine of the class described having, in combination, a gripper for engaging an upper, manual means for operating the gripper to pull the upper, means for locking the gripper against movement in a direction to relax the tension of the upper, and means for imparting a supplemental pulling movement to the gripper.

26. A machine of the class described having, in combination, a gripper for engaging an upper, manual means comprising a hand lever for operating the gripper to pull the upper, means for locking said lever against movement in a direction to relax the tension 10 of the upper, and power operated means independent of said lever for imparting a supplemental pulling movement to the gripper.

27. A machine of the class described having, in combination, a gripper for engaging an upper, means for operating said gripper to cause it to pull the upper and to come to rest with the upper under tension, manual means for operating the gripper to increase the tension of the upper, power 20 driven mechanism for subsequently overlaying and fastening the upper, and means incidentally operative during the operation of said overlaying mechanism for further moving the gripper to increase the tension 30 of the upper.

28. A machine of the class described having, in combination, grippers for engaging an upper at opposite sides of a last, means for operating said grippers to pull the upper, manual means for operating said grippers in unison to increase the tension of the upper, and power driven means for subsequently imparting an additional pulling movement to the grippers.

29. A machine of the class described having, in combination, a gripper for engaging an upper, means for operating said gripper to subject the upper to a yielding pull, manual means for operating the gripper to increase the tension of the upper, and power operated means for imparting a final pulling movement of definite extent to the gripper.

30. A machine of the class described having, in combination, a gripper for engaging an upper, power operated means for moving said gripper to pull the upper, manual means for moving the gripper to increase the tension of the upper and for locking it to hold the tension, and power operated means constructed and arranged to assume positive control of the gripper subsequently and to overdraw and fasten the upper.

31. A machine of the class described having, in combination, a plurality of grip-

pers for engaging an upper on a last, means for operating said grippers to pull the upper, a device common to the several grippers for holding them against retractive movement, and power operated means for rendering said device effective to hold the grippers.

32. A machine of the class described having, in combination, means for gripping an upper on a last, means for effecting relative movement of said gripping means and the last to pull the upper, means for moving said gripping means inwardly over the last to overdraw the upper, and power operated mechanism timed to impart upper pulling 75 operative movement to the gripping means to tighten the upper in the overdrawing movement of said means.

33. A machine of the class described having, in combination, means for gripping an upper on a last, means for operating said gripping means to pull the upper, means for moving the gripping means inwardly over the last to overdraw the upper, and mechanism for imparting to the gripping 85 means a further movement in the same direction as its first pulling movement in the overdrawing of the upper.

34. A machine of the class described having, in combination, means for gripping an upper on a last, means for effecting relative movement of said gripping means and the last to pull the upper and for then holding the upper under tension with the machine at rest, means for moving said gripping means 100 inwardly over the last to overdraw the upper when the machine is again started, and mechanism arranged to be operated after the machine has thus been started to impart to the gripping means a pulling movement 105 to tighten the upper.

35. A machine of the class described having, in combination, means for gripping an upper on a last, power operated means for effecting relative movement of said gripping means and the last to pull the upper in one stage of the cycle of operations of the machine and for causing the gripping means to draw the upper inwardly over the bottom of the last at a later stage in the cycle of 110 operations after the machine has been again started, and mechanism arranged to be operated in said last-named stage of the cycle of operations to move the gripping means in a direction to change the tension of the 115 upper.

36. A machine of the class described having, in combination, an upper engaging gripper, means for effecting relative movement of said gripper and a last to pull the 125 upper, means for causing the gripper subsequently to draw the upper inwardly over the bottom of the last, and mechanism arranged to impart to the gripper a movement in a direction to change the tension of the upper 130

during the overdrawing movement of the gripper.

37. A machine of the class described having, in combination, means for gripping an upper on a last, means for effecting relative movement of the gripping means and the last to pull the upper and for then causing the gripping means to draw the upper inwardly over the bottom of the last, mechanism for moving the gripping means in a direction to increase the tension of the upper before the overdrawing movement is completed, and power operated means for initiating the operation of said mechanism.
38. A machine of the class described having, in combination, upper gripping means, power driven means for operating said gripping means to pull the upper and for then causing the gripping means to hold the upper under tension with the machine at rest, and means automatically operative upon a subsequent starting of the machine to impart to the gripping means a second movement in substantially the same direction as its first movement to increase the tension of the upper.

39. A machine of the class described having, in combination, means for gripping an upper on a last, power operating means, means for causing said operating means to effect a relative movement of the gripping means and the last to pull the upper yieldingly, and means for causing said operating means subsequently to effect a positive relative movement of the gripping means and the last automatically predetermined in extent to increase the tension of the upper.

40. A machine of the class described having, in combination, means for gripping an upper on a last, means for operating said gripping means to cause it to pull the upper and then to hold the upper under tension with the machine at rest, means for operating the gripping means after the machine is again started to draw the margin of the upper inwardly over the bottom of the last, and means arranged to be rendered operative automatically upon said starting of the machine to lock the gripping means against yielding movement in a direction toward the plane of the shoe bottom.

41. A machine of the class described having, in combination, means for gripping an upper on a last, means for operating said gripping means to cause it to pull the upper and then to hold the upper under tension with the machine at rest, means for causing said gripping means to draw the margin of the upper inwardly over the bot-

tom of the last when the machine is again started, and means arranged to be operated automatically after the machine has been thus started to lock the gripping means against yielding movement in a direction toward the plane of the shoe bottom, said locking means being adjustable to vary the time of its operation with respect to the overdrawing movement of the gripping means.

42. A machine of the class described having, in combination, a gripper for engaging an upper on a last, means for effecting relative movement of said gripper and last to pull the upper and for causing the gripper then to hold the upper under tension with the machine at rest, means for operating the gripper when the machine is again started to draw the margin of the upper inwardly over the bottom of the last, and means arranged to be rendered operative automatically upon said starting of the machine to lock the gripper for holding the tension of the upper, said locking means being arranged to remain operative to lock the gripper until the overdrawing movement of the gripper has been completed.

43. An upper pulling machine having, in combination, an upper engaging gripper, a shoe bottom rest, and means automatically operative in the cycle of operations of the machine to effect relative movement of said gripper and rest to pull the upper yieldingly and subsequently without attention from the operator to supplement said yielding pull by an unyielding pull.

44. An upper pulling machine having, in combination, an upper engaging gripper, power driven means for operating said gripper to pull the upper yieldingly, and additional power driven means arranged to come automatically into action at a determinate time in the cycle of operations for moving the gripper unyieldingly to increase the tension of the upper.

45. An upper pulling machine having, in combination, an upper engaging gripper, a power driven operating member, a yielding connection between said member and the gripper for operating the gripper to pull the upper yieldingly, and mechanism automatically operative at a determinate time in the cycle of the machine to substitute an unyielding connection for said yielding connection for further pulling the upper.

In testimony whereof I have signed my name to this specification.

JOHN T. LANCASTER.

It is hereby certified that in Letters Patent No. 1,362,631, granted December 21, 1920, upon the application of John T. Lancaster, of Haverhill, Massachusetts, for an improvement in "Upper-Pulling Machines," an error appears in the printed specification requiring correction as follows: Page 7, line 81, claim 32, strike out the word "operative"; and that the said Letters Patent should be read with this correction therein that the same may conform to the record of the case in the Patent Office.

Signed and sealed this 8th day of March, A. D., 1921.

[SEAL.]

M. H. COULSTON,
Commissioner of Patents.

Cl. 12—4.
